Charles R. Searle.

UNITED STATES PATENT OFFICE.

JOSEPH MAZANEC AND FRANK SKARDA, OF NEW YORK, N. Y.

DESIGN FOR A MULE.

54,218.

Specification for Design.

Patented Nov. 18, 1919.

Application filed June 18, 1919. Serial No. 305,187. Term of patent 14 years.

To all whom it may concern:

Be it known that we, JOSEPH MAZANEC, a citizen of Czechoslovakia, residing in the city of New York, borough of Manhattan, in the county and State of New York, and FRANK SKARDA, a citizen of Czechoslovakia, residing in the city of New York, borough of Brooklyn, in the county of Kings and State of New York, have invented a new, original, and ornamental Design for Mules,

of which the following is a specification, reference being had to the accompanying drawing, forming part thereof.

The figure is a perspective view of a mule, showing our new design.

We claim:—

The ornamental design for a mule, as shown.

JOSEPH MAZANEC.
FRANK SKARDA.
